UNITED STATES PATENT OFFICE

GEORGE WESLEY BOYER, OF NEW YORK, N. Y., ASSIGNOR TO STANDARD BRANDS INCORPORATED, OF NEW YORK, N. Y., A CORPORATION OF DELAWARE

DESIGN FOR A BAG OR ANALOGOUS ARTICLE

Application filed December 16, 1930. Serial No. 38,009. Term of patent 14 years.

To all whom it may concern:

Be it known that I, GEORGE WESLEY BOYER, a citizen of the United States, residing at 39 Charles Street, New York, New York, have invented a new, original, and ornamental Design for a Bag or Analogous Article, of which the following is a specification, reference being had to the accompanying drawing, forming part thereof.

The two different varieties of lining on the drawing are indicative of contrasting colors.

I claim:—

The ornamental design for a bag or analogous article, as shown.

GEORGE WESLEY BOYER.
